HINGE GUARD FOR SOFA BEDS

Herbert W. Neunherz, Gardner, Mass.

Application September 17, 1941, Serial No. 411,189

2 Claims. (Cl. 16—146)

This invention relates to hinge constructions for sofa beds, and more particularly to such hinge constructions having guards to protect the sofa upholsteries from wearing and snagging on the movable hinge parts, and to prevent interference of the upholstery with hinge parts operation.

Objects of the invention include the provision of a simplified but efficient hinge construction of the sofa bed type; the provision of a hinge having means to latch it in sofa position of the seat and back rest units and means quickly and easily unlatching the same to form the bed, with a guard of particular construction to prevent interference and wearing of the mattresses, etc., occurring when the hinge latching parts are actuated; and the provision of a simple but effective guard and gauge for latching hinges of the sofa bed type.

Other objects and advantages of the invention will appear hereinafter.

Reference is to be had to the accompanying drawings, in which—

Fig. 1 is a side elevation of a hinge and guard as applied to a sofa bed, and showing the parts in bed-forming position thereof;

Fig. 2 is an enlarged side elevation of the hinge and guard with parts broken away, showing the parts just prior to latched condition of the hinge;

Fig. 3 is a side elevation of the hinge and guard showing the parts just prior to unlatching the hinge;

Fig. 4 is a perspective of the guard; and

Fig. 5 is a cross-section on line 5—5 of Fig. 3.

This invention relates to that type of sofa bed in which the seat and back-rest units or mattresses are pivoted together along corresponding edges, and are swingably mounted, by means of a pair of end hinges of particular construction, so that the back-rest may be automatically latched in raised position, or unlatched to be swung, with the seat, to horizontally aligned bed-forming position. The hinge structure employed necessarily has moving latch parts, which tend to rub against and snag on or tear the upholstery and to become entangled in the same and thus prevent the proper operation of the hinges, but by providing a novel hinge-guard and gauge device this objection is overcome. Only one hinge is here disclosed, but it is to be understood that there is another similar but reversed hinge at the other end of the sofa bed.

In Figs. 1 and 3, the numeral 10 indicates the back frame member of a sofa bed, and 12 indicates an end board. The back rest is shown at

14 and its mattress at 16, while the seat is labeled 18 and its mattress 20. An angle iron support 22 is screwed or bolted to the top edge of the board 12 and relatively long and short arms 24 and 26 are pivoted to the vertical side of this iron. Short arm 26 is pivoted at 28 to the top portions of a pair of hinge plates 30, 32, and the pivot 28 forms a pivot connection for these plates.

Plate 30 is secured to the back rest 14 and plate 32 to the seat 18, and the plates are so arranged as to be separated at the seat and back rest but incline towards each other at the pivot 28. In order to locate the plates in the same plane, one plate is offset as at 34 to accommodate the other.

Long arm 24 is pivoted to plate 30 as at 36, and therefore it will be seen that the entire hinge structure, together with the back rest and seat, may be swung upon arms 24, 26, to locate the adjacent edges of the mattresses either as shown in Fig. 1, or more towards the back 10, in which position the long arm ensures that the back rest will be positioned substantially vertically. However, since the hinge so far described will not maintain the parts in this position, a latch must be provided.

A relatively long lever 38 is pivoted at one end at 40 to hinge plate 32, and a spring 42 is arranged to continuously urge this lever counterclockwise as seen in Figs. 1, 2, and 3. At its free end, lever 38 is provided with a notch 44 having a slight undercut 46 adjacent a cam surface 48, and a pin 50 is provided on hinge plate 30. Hence if the pin 50 engage in undercut 46, the spring will prevent their dislodgement, and the hinge plates, hence the back rest and seat, will be rigidly connected. Thus, supposing the seat 18 to be lifted at its front edge, so as to pivot about 23, the lever 38 will be retracted from its position shown in Fig. 1, and the pin will engage in the notch. This condition will occur in Fig. 2, if the lever 38 be drawn slightly to the right. As soon as this latching action takes place, the seat may be swung down, thus raising the back to a sitting position, and the weight of the parts will maintain the structure in sofa form.

A small pawl 52, notched at 54, is pivoted to the lever at 56, adjacent notch 44. This pawl is freely swingable, but lever 38 is provided with a stop 58 against which the pawl normally rests under the influence of gravity. However, if the parts as shown in Fig. 2 be swung further than before recited, to position as shown in Fig. 3, the notch 54 will engage pin 50, even

though the latter is also in notch 44. Therefore, when the seat 18 is swung clockwise, Fig. 3, the pawl 52 will raise lever 38 up out of engagement with pin 50, against the action of the spring, and the latch is broken, so that back rest and seat are no longer rigidly connected and may assume the position of Fig. 1. It will be seen that the construction as above described provides easy transfer of the parts from sofa to bed and vice versa merely by a simple manipulation of the seat 18.

It will be seen from the above that pawl 52 is a very important element in the successful operation of the sofa bed, and that it is pivotally mounted on the movable lever 38 by means of a pin at 56. These parts are quite liable to snag on the sofa bed upholstery, especially that of the end arms, and cloth often becomes wedged between member 14 and the pawl, thus preventing the operation thereof. When this happens, either to the pawls at both ends of the sofa bed or only to one pawl, the operator has a tendency to try to force the parts, thus twisting them and causing permanent damage.

Therefore, however well the above recited structure operates, the lever 38 and pawl 52, and especially pin 56, are liable to become entangled in the mattresses and upholstery, interfering with their operation and to snag and tear the upholstery of the mattresses, especially in the region of the back rest 14. A special guard structure which will prevent interference with the operation of the device has been provided, and this guard is shown per se in Fig. 4. A flat triangular plate 60 having curved edges 62 is formed with a flange 64 on one side and out-turned ears 66 are provided for attachment thereof to hinge plate 30 as by welding or rivets 68. The flange 64 is arranged to lie on a curve generally paralleling the movement of the free end of lever 38, and between the latter and back rest 14. The non-flanged or open sides 62 of the plate 60 allow the lever to move freely through the guard, as will be apparent from a comparison of Figs. 1 and 3. Pin 50 extends thru the hinge plate 30 and plate 60 and serves to aid in retaining the parts.

It is to be particularly noted that the extremes of range movement of pin 56 are covered by the guard, see Figs. 1 and 3, so that upholstery, threads, etc., cannot become entangled in the parts, and lever 38 and pawl 52 are enclosed during the operating range of their movements.

Flange 64 provides a closure element at the bottom of the latch movement range, and forms a gauge for correct assembly of the entire hinge on the end board 12 and back rest 14. It is common experience to find that wooden members, such as the end board and back rest referred to, vary considerably in their dimensions, and if the back rest is too thick, for instance, or the

end board too narrow, the free end of lever 38 will impinge on and even be stopped by the back rest.

In assembling the present hinge, the guard 5 and gauge element 60 is positioned on hinge leaf 30 by pin 50 and riveted at 68, so that flange 64 will always be uniformly located. Plate 22 is set in the only position possible on board 12, and hinge leaf 30 is correspondingly located by its flange on back rest 14. If flange 64 does not just fit back rest 14, then the parts are incorrect, and this condition can be seen at a glance by reason of the flange. If it is spaced from member 14, the latter must be discarded; if it cannot be assembled due to too great a thickness of member 14, then the latter can be planed down to fit. Hence the flange guard has a double function and by its use perfect hinge action is always obtained, thus improving the quality of the goods.

It will be seen from the above that a simple, efficient, and positively acting latch hinge has been provided, the latch parts having an efficient guard to prevent damage to the upholstery of the sofa bed.

Having thus described my invention and the advantages thereof, I do not wish to be limited to the details herein disclosed, otherwise than as set forth in the claims, but what I claim is:

1. A device of the class described comprising a support, pivoting seat and back rest elements on the support, latching means therefor comprising a hinge leaf for each element, a flange on at least one hinge leaf, means forming an aperture in said one hinge leaf, said aperture being located a predetermined distance from the flange, a plate having a pin therein for entry into said aperture to secure the plate to said one hinge leaf, means for spacing the plate and said one hinge leaf, said last named means and the pin locating said plate in predetermined parallel relation to said one hinge leaf and its flange, a flange on the plate spaced from the first named flange a predetermined distance by said plate spacing means and the pin, a frame member for the seat element having a width to fit between the flanges, a free-ended lever on the other hinge leaf, a notch in the lever to receive the pin to latch the hinge leaves together, said lever being selectively movable to disengage the pin and notch, said plate flange guarding the free end of the lever during a part of its movement adjacent the frame member, said lever being located in a plane intermediate the plate and one hinge leaf.

2. A device according to claim 1 wherein the movement of the free end of the lever is along a curve determined by the pin acting as a rest for the lever, and wherein said plate flange is curved to conform in general to a part of said movement.

HERBERT W. NEUNHERZ.
